(57) CLAIM

The ornamental design for an ornament having a tomb with stone rolled away, as shown and described.

DESCRIPTION

A portion of the disclosure of this patent document contains material to which a claim for copyright is made. The copyright owner has no objection to the facsimile reproduction by anyone of the patent document or the patent disclosure, as it appears in the Patent and Trademark Office patent file or records, but reserves all other copyright rights whatsoever.

FIG. 1 is a front elevation view of an ornament having a tomb with stone rolled away showing my new design;

FIG. 2 is a side elevation view thereof;

FIG. 3 is an opposite side elevation view thereof;

FIG. 4 is a top plan view thereof;

FIG. 5 is a bottom plan view thereof;

FIG. 6 is a rear view thereof;

FIG. 7 is a perspective view thereof; and,

FIG. 8 is a front elevation view thereof, showing the ornament having a tomb with stone rolled away in a configuration of use.

The broken lines shown in FIGS. 2-4 illustrate portions of the ornament having a tomb with stone rolled away which form no part of the claimed design. The other broken lines shown in FIG. 8 illustrate environmental subject matter and form no part of the claimed design.

The ornament includes a pin-type, pendant, or stick-on adornment in the nature of jewelry or a hanging decoration.
